his attorney.

UNITED STATES PATENT OFFICE.

JAMES B. ANDERSON, OF SHALER TOWNSHIP, ALLEGHENY COUNTY, PENNSYLVANIA.

CUTTING-TORCH.

1,297,053.

Specification of Letters Patent. Patented Mar. 11, 1919.

Application filed August 27, 1918. Serial No. 251,638.

To all whom it may concern:

Be it known that I, JAMES B. ANDERSON, citizen of the United States, and residing in the township of Shaler, in the county of Allegheny and State of Pennsylvania, have invented or discovered new and useful Improvements in Cutting-Torches, of which the following is a specification.

My invention consists in certain new and useful improvements in cutting torches for use with oxygen and a combustible gas, such as acetylene or one of its possible substitutes, and more especially the present improvement relates to the tip and head structure of the torch.

The object I have in view is to obtain, *inter alia*, the following improved results: The more intimate and complete mixing of the low pressure oxygen and the combustible gas into a homogeneous heating gas, thereby effecting a very marked economy in the volume and pressure of gas required, while at the same time obtaining a very substantial increase of heat furnished. The economy is therefore extended to the volume and pressure of the high pressure oxygen required for cutting. Again, I have in view the use of less expensive substitutes for acetylene, such as butane and other gases which are now regarded as more or less worthless by-products. Another object is the prevention of the flame blowing out at low pressure or blowing back into the torch.

I accomplish these ends by providing a base and tip structure which has, in addition to the usual axial passage for the high pressure oxygen, an annular mixing chamber into which the low pressure oxygen and the combustible gas are admitted and wherein they are partially mixed; then an annular chamber, into which the partially mixed gases are led, which is characterized by a plurality of vanes or blades, preferably of angular shape, intersecting the chamber to thoroughly break up and intermingle the streams of entering gases so that a completely mixed gas is formed; a third annular chamber into which the composite heating gas is admitted from the vane chamber and which serves to establish a uniform supply of the same, and finally a series of passages, concentric with the high pressure oxygen passage, through which the composite gas passes to the outer end of the tip.

In the accompanying drawings, which are merely intended to illustrate the principles of my invention without limiting the scope thereof to the construction shown, Figure 1 is a central section through a torch head and tip embodying my invention; Fig. 2 is an elevation of the tip dismounted from the head; Fig. 3 is a butt end view of the tip; Fig. 4 is a cross section taken along the line IV—IV in Fig. 2, and Fig. 5 is a similar view taken along the line V—V in Fig. 2.

The following is a detailed description of the drawings.

A represents the head of a torch, shown as of the design more fully described in my pending patent application Serial Number 228,558, filed in the United States Patent Office on April 15th, 1918. Said head is shown provided with a high pressure oxygen chamber 1 into which leads the supply tube 2. 3 is a valve seat connecting said chamber with the axial bore 4 of an externally tapered nozzle 5 which is preferably integral with the head. 6 is a spring seated valve engaging said valve seat and controlled by the operating rod 7.

An annular low pressure oxygen chamber 8 surrounds the base of the nozzle 5, and into said chamber leads the low pressure oxygen tube 9. 10 is an annular, exteriorly threaded flange, integral with the head and concentric with but spaced away from the nozzle 5. A supply tube 11 for combustible gas leads into the interior of said flange near its base.

B is a demountable tip member, more clearly shown in Figs. 2, 3, 4 and 5. Said tip is provided with the usual axial bore 12 whose inner end is flared to fit over the nozzle 5 and form a tight joint therewith. 95 The butt end 13 of said tip is cylindrical and at its extremity is provided with a circumferential collar 14 which fits up in the interior of the flange 10. It is evident that the butt end of the tip forms the closure of the low pressure oxygen chamber 8.

15 is a second circumferential collar on the inner end of the cylindrical butt of the tip. When the tip is inserted in the head an annular chamber 16 is formed between the tip 105 and the inner wall of flange 10. This is the combustible gas chamber, supplied by the tube 11.

17 represents an annular series of longitudinal passages in the cylindrical butt of 110

the tip, concentric with its axial bore and leading, when the torch is assembled, from the low pressure oxygen chamber 6, 18 represents an annular series of radial ports or slots in the collar 15 leading inwardly from the chamber 16 to the passage 17.

The intermediate portion of the tip 13 is tapered, as shown, while its outer end is preferably cylindrical but of less diameter than its butt.

C is the outer sleeve which is adapted to be slipped over and singly fit the tip B, and is provided on its inner end with a circumferential collar 19 which fits into the flange 10 of the head. D is the cylindrical clamping nut threaded to be screwed up on the exterior threads of the flange 10 and provided with an annular shoulder 20 which bears against the collar 19 or the sleeve C. The bore of the nut is preferably cylindrical so that a direct wedging action is exerted on the tip to force it up into the flange 10 into tight union. I prefer to provide an annular packing ring or gasket 21 between the shoulder 20 and the collar 19 to make a gas-tight joint.

An annular series of slots 22 in the perimeter of the tip B lead from the outer ends of the passages 17 and from the ports 18 to an annular chamber 23 within the sleeve C formed by a reduction of the diameter of the tip. Into this chamber 23 the low pressure oxygen from the chamber 6 and the combustible gas from the chamber 16 both pass and therein said gases are partially intermixed. The partially mixed gases thence pass into a mixing chamber 24 within the sleeve C characterized by a plurality of vanes extending radially from the tip and intersecting the chamber. These vanes, as will be seen in Figs. 2 and 4, are arranged in annular series around the tip and the individuals of a series are preferably aligned with the individuals of adjacent series. These vanes act to break up and thoroughly intermingle the streams or currents of partially mixed gases entering from the chamber 23, so that a composite and uniform heating gas is formed in chamber 24, which composite gas thence passes to a chamber 25 also formed within the sleeve C by a reduction of the diameter of the tip. This cham-

ber 25 provides a volume of gas of uniform pressure which is led to the outer end of the tip through the annular series of longitudinal passages formed by slotting the perimeter of the tip. It will be noticed that these passages converge outwardly near their inner ends, owing to the taper of the tip and sleeve, but their outer ends are parallel with the central bore 12, so that a cylinder of heating gas ignited in flame is formed surrounding and concentric with the oxygen cutting flame.

In the use of my improved tip structure 26 I have found that such a complete and uniform mixture of the two gases is effected that I require less pressure and volume of low pressure oxygen and combustible gas, because the combustion of the heating gas 27 at the tip mouth is complete and a much higher temperature is obtained. This, of course, enables me to use a less pressure and volume of high pressure oxygen for the cutting flame. It also enables me to use as a substitute for the combustible gas any one of a number of gases which have hitherto been regarded more or less as waste products and are therefore less expensive than acetylene. I have found that the torch flame 28 will not blow out even at pressures which were impossible to use with the old style torches; there is no danger of the flame blowing back into the torch, and the torch may be readily lighted with a match. 33

What I desire to claim is—

In a cutting torch, a head and tip structure provided with an annular low pressure oxygen inlet chamber, a combustible gas inlet chamber, an annular mixing chamber 23 intersected by baffling means, an annular series of passages connecting said inlet chambers with said mixing chamber, a second annular series of passages connecting said mixing chamber with the outer end of the tip, a high pressure oxygen inlet chamber, and a passage, axial of said annular chambers and annular series of passages, connecting said high pressure oxygen inlet chamber with the outer end of the tip. 34

Signed at Pittsburgh, Pa., this 26th day of August, 1918.

JAMES B. ANDERSON.
